UNITED STATES PATENT OFFICE.

CARROLL E. DODSON, OF KANSAS CITY, MISSOURI.

VANITY CASE.

Application filed April 13, 1925. Serial No. 22,706.

This invention relates to vanity cases, and the primary object thereof is to provide a vanity case having powder-containing means, a mirror, a powder puff and preferably a rouge compartment, all arranged in a compact manner so that the entire vanity case will take up very little room. The vanity case contemplated by this invention is especially designed to contain loose powder, in contra-distinction from those vanity cases utilizing cakes or compacts. A device adapted to contain a compact may be easily constructed, but compacts are unpopular due to the belief that the compacted powder does not readily adhere to the powder puff and because it is hard and rough as compared to the soft and velvety quality of loose powders. However, it is difficult to retain loose powder in the receptacle in such a manner that it will be ready to be applied to the powder puff and yet held in place so that liability of its spilling will be prevented. To this end I have provided a loose-powder containing pan in the case so associated with a screen-like cover for the pan, that the powder will at all times be forced against one side of the cover in such a manner that it will sift through the fine meshes of the screen, but not enough to spill.

I preferably make the screen of fabric and appropriately hold it to a rigid part of the cover so it will be relatively taut. Therefore, when the powder is pressed against one side of the screen and the powder puff is rubbed over the opposite side of the screen, enough of the impalpable powder will adhere to the powder puff to meet the requirements of such devices.

I may also employ a rouge compartment in the top of the lid, with a mirror serving a dual purpose of a reflector and a closure for the rouge compartment or pan. An important feature of the invention is that these various parts are so relatively arranged that they may be telescoped or nested, thereby enabling the manufacturer to provide a vanity case, the thickness of which will be reduced to a minimum, and another important feature of the invention is that the powder pan is so arranged in the bottom of the case that the powder may be introduced into the pan without liability of spilling, then the cover may be moved into position to make a comparatively closed expandible and contractible chamber in which the powder is located, and the parts will be so arranged that

the powder cannot be extruded from any part of the chamber except through the meshes of the screen.

The novelty of the invention will be clearly understood by reference to the following description in connection with the accompanying drawings, in which

Fig. 1 is a perspective view of the vanity case with the lid raised and the mirror swung on its pivot to expose the rouge pocket or pan.

Fig. 2 is a similar view showing the cover in raised position to expose the interior of the loose-powder pan.

Fig. 3 is a cross sectional view through the vanity case in closed position.

Fig. 4 is a disassociated view of the spring member, the loose-powder pan, and the guide for the pan, and

Fig. 5 is a perspective view of the mirror-supporting member.

The vanity case is illustrated as comprising two main members, one of which is a bottom 1, and the other a lid 2. Both of these are hollow and they are hinged at 3, the pintle 4 of the hinge being also effective in hinging an intermediate cover to the members 1 and 2, the cover being shown as comprising a metallic ring 5 having an inturned, receding beveled face 6 with a cylindrical flange 7 at its inner circumference adapted to receive a clamping ring 8 between which and the flange 7, is the edge of a screen 9 preferably of fabric, the mesh of which is of sufficient fineness to obstruct a free flow of powder through the screen.

Co-operating with the cover is a loose-powder receiving pan comprising a disc 10 with a peripheral upstanding flange 11 to provide a relatively shallow receptacle for the powder indicated at 12 in Figure 3. The bottom 10 of the pan is shown as provided with two slots 13 and 14 which receive the struck-up fingers 15 and 16 on the spring-carrying disc 17, the ends of the fingers being bent over the edges of the slots as clearly shown in Figure 2 so that the spring-carrying disc 17 and the pan are firmly secured together. For convenience I may strike from the disc 17 a plurality of segmental spring fingers 18 which are adapted to bear against the bottom wall of the member 1 as shown in Figures 3 and 4. These fingers yieldingly support the pan, but tend to force it against the screen. The up-standing flange 11 of the pan is guided between the short in-

turned wall 19 of the guide ring 20 and the clamping ring 7 so that it will be maintained concentric with the screen. The larger flange or outer wall portion 21 of the ring 20 is provided with outstanding struck-up fingers 22 which may engage under the shoulder 23 of the bottom member 1 so that the guide ring or member 20 will be held rigid with respect to the member 1. The inner edge portion of the ring 5 and the short flange 19 of the ring 20 provide a guide or recess for the upper edge of the flange 11 of the powder receiving pan, and the disc 17 is of greater diameter than the diameter of the pan, so that the projecting edge portion 24 of the disc 17 may contact with the lower edge of the flange 19 when the spring fingers 18 have moved the pan a determined distance, and since the inner edge of the flange 11 snugly fits around the clamping ring 8, it will be apparent that the powder cannot pass out of the chamber formed by the pan and the screen except through the meshes of the screen. It will also be apparent that since the outer edge of the ring 5 frictionally engages the constricted portion 25 of the member 1, that it will be held against accidental movement on the hinge 3. The constricted portion is formed by the shoulder 23, and over it fits the outer edge of the lid 2.

In the lid 2 is a rouge-pocket forming member having an inclined outer ring portion 26, the edge of which frictionally engages the outer wall of the lid. There is an intermediate web portion 27 inclined in a direction opposite to the angle of inclination of the portion 26. The web portion carries a depression or pocket 28 in which may be received a cake 29 of rouge or similar cosmetic, and over the cake 29 may be placed a puff 30. The pocket or pan 28 may be closed by a closure adapted to move against the open portion of the pan or pocket, and to this end I provide a mirror-carrying disc 31 with a struck-out supporting ear 32 having an opening 33 coinciding with an opening 34 in the web 27, the ear 32 being secured to the web 27 preferably by a hollow rivet 35, and since the ear 32 is at an angle to the disc 31 but parallel with the web 27, it is obvious that when the disc is swung about its pivot to uncover the pocket 28 it will be tilted at an angle to the lid 2 as clearly shown in Figure 1. The tilting of the disc 31 with its mirror 36 has an advantage in that the mirror is swung at the proper angle for the user to observe the reflection of her features while the bottom of the case is at a horizontal plane. In the web 27 is formed a segmental rib 37, one end 38 of which acts as a stop to limit the swinging movement in pocket-uncovering position, and the other end 39 limits the movement of the mirror and disc 31 when

it is swung to pocket-closing position. Attention is here called to the fact that when the disc and mirror are swung to closing position they will be nested within the concave portion formed by the inwardly curved web 27, so that notwithstanding the fact that the mirror would be tilted at an angle to a horizontal plane passing through the middle of the case when it is in open position, it will move back into a nested position when it is swung into the position shown in Figure 3, and since the beveled portion 6 of the ring 5 is at substantially the same angle as the ring portion 26, and further inasmuch as the beveled portion 6 and the flange 7 form a recess or pocket, it is obvious that a recess or space will be provided for the loose-powder puff 40 which may lie between the mirror and the screen, it being apparent by reference to Figure 3 that the mirror will also lie within the part of the flange 7, therefore the necessity for making a thick case will be eliminated, and for convenience I may introduce a flat spring 41 in the pocket 42 formed by the web 27 and the cover, the spring extending through the web with a projecting outer end 43 which may constitute a clip for the rouge puff 30. The lid member and bottom member may be fastened together by providing a notch 44 in the bottom and a catch 45 in the lid to engage the notch, but other fastening means may be employed if desired.

Assuming the parts to be assembled and further assuming that the natural position for the bottom is in a horizontal plane, it will be apparent that when the lid is swung back to the position shown in Figure 1, the mirror may be swung to uncovering position so that it will practically be in a vertical plane, but that when it is moved to closing position it will be in the same plane as the lid. It will also be apparent that the loose powder may be conveniently placed in the pan by raising the intermediate cover without danger of spilling the powder, as often happens where the powder is initially placed in the screen frame in which case it becomes necessary to invert the case in order to re-fill it. It will further be apparent that all the necessary parts of a modern vanity case are incorporated in the present invention in a compact manner, and that the parts may be easily assembled and dis-assembled for renewals, inspection or repairs.

What I claim and desire to secure by Letters-Patent is:

1. A vanity case comprising a hollow bottom, a pan mounted for follower movement in the hollow bottom, a hinged cover having a screen portion normally overlying the pan, and a hinged lid for the case. 125

2. A vanity case comprising a hollow bot- 130

tom, a pan mounted for follower movement in the bottom, a spring member beneath the pan for inducing the follower movement, a hinged cover having a screen portion normally overlying the pan, and a hinged lid for the case.

3. A vanity case comprising a hollow bottom, a keeper ring in said hollow bottom, a pan telescopically movable in the keeper ring, a pusher member beneath the pan, a hinged cover for the pan, having a screen portion through which contents of the pan may pass, and a lid for enclosing the pan and cover.

15 4. A vanity case comprising a hollow bottom, a pusher member in said bottom comprising a follower disk and spring fingers for engaging the bottom and urging the disk outwardly, a pan seated on said disk, a hinged cover having a screen portion overlying the pan, and a lid hinged to the bottom and normally enclosing the pan and its cover.

5. In a vanity case, a hollow bottom member having an inturned flange, a keeper ring within the bottom member having latch members for engaging said flange, a pusher member within the bottom member comprising a follower disk and spring fingers, a pan seated on said disk within the ring, a cover member comprising a ring-shaped body having an internal flange projected into the pan and having a central screen portion carried by the ring-shaped body

35 to retain contents of the pan, and a lid for

the case, the bottom member, the cover and the lid having hinged connection.

6. A vanity case comprising a hollow bottom, a lid, an intermediate cover, the cover having a screen-like wall, a loose-powder containing pan yieldingly supported in the bottom for maintaining the loose powder at all times in contact with the screen, a rouge pan in the lid having a beveled portion, and a mirror pivoted on the beveled portion of the pan.

7. A vanity case comprising a hollow bottom, a lid, an intermediate cover, the cover having a screen-like wall, a loose-powder containing pan yieldingly supported in the bottom for maintaining the loose powder at all times in contact with the screen, and stop means in the bottom for limiting the movement of the pan toward the screen, said stop means comprising a ring held in the bottom and having means in the path of a projecting part of the pan.

8. A vanity case comprising a hollow bottom, a hollow lid and an intermediate cover all hinged together, the cover having a screen-like wall and provided with a recessed portion in which the wall is located, a yieldingly supported loose-powder containing pan in the bottom movable toward and away from the cover, and a mirror support carried by the lid having a mirror adapted to be received in the recess.

In testimony whereof I affix my signature.

CARROLL E. DODSON.
